WILLIAM H. WINSLETT. ^{Inventor}

By Randolph J. Attorneys

UNITED STATES PATENT OFFICE.

WILLIAM HENRY WINSLETT, OF NIXON, TEXAS.

WINDMILL.

1,399,282.

Specification of Letters Patent.

Patented Dec. 6, 1921.

Application filed October 19, 1920. Serial No. 417,908.

To all whom it may concern:

Be it known that I, WILLIAM H. WINSLETT, a citizen of the United States, residing at Nixon, in the county of Gonzales and State 5 of Texas, have invented certain new and useful Improvements in Windmills; and I do hereby declare the following to be a full, clear, and exact description of the invention, such as will enable others skilled in 10 the art to which it appertains to make and use the same.

This invention relates to a wind mill, and the object is to provide means for resiliently connecting or mounting a pump rod and pitman for transmitting movement from the crank shaft carrying the wheel, in order that the elements may be properly balanced, and wear due to unevenly distributed weight or pull may be to a great extent eliminated. 15 A further object is to provide particular means for connecting the pump rods with a stationary element mounted on the supporting structure, whereby the aforesaid results are secured.

20 A still further object is to provide, in connection with a transverse element adjustably connected with a pump rod, a plurality of coiled springs connected with the adjustable element and with stationary elements 25 mounted on the supporting structure, the springs serving to compensate for the uneven action due to the variable pull on the pitman and pump rod.

With the foregoing and other objects in 30 view, the invention consists in the novel construction, combination and arrangement of elements hereinafter described and claimed.

In the accompanying drawings Figure 1 is a view in side elevation.

40 Fig. 2 is a view in vertical section, the lower portion of the supporting structure being omitted.

Figs. 3 and 4 are detail views showing the 45 arrangement of the springs and the devices by means of which they are connected respectively with the pump rod and the supporting structure.

The main frame, or supporting structure, is designated 10, the upwardly extended corner elements or legs are shown at 11, 12, 13 50 and 14, being connected by lower horizontal braces 15 and intermediate horizontal braces 16 and diagonal braces 17.

The wind wheel *per se* is designated 20, 55 being mounted on crank shaft 21 journaled

in the forked ends 22 and 23 of a supporting frame 24. The latter is firmly supported in a member 25 which constitutes a connecting element between the frame 24 and the supporting structure. 60

A pitman 27 connects the crank shaft with the pump rod 28, and the latter is provided with a transverse element 30 adjustably mounted on the rod and including a plurality of outwardly extending arms 31. This 65 bracket is clamped in its adjusted position, by means of bolts or other suitable securing devices 32.

A spider like member 34 is connected with the elements of the supporting structure, at 70 about the point shown, and between this spider and the adjustable transverse element 30, are a plurality of coiled springs 35. In the present instance I have shown four of the springs, the springs being of suitable 75 size and tension being adjusted in an obvious manner.

In practical use, this device is found to add greatly to the efficiency of the apparatus, and make it possible to use a wheel of relatively small diameter compared with the 80 work to be performed. It is obvious that modifications in construction may be made within the scope of the appended claims, and that the use of the resiliently mounted 85 rod and pitman is not limited to a windmill and pump, the attachment being equally serviceable in other connections.

The wind mill shown in the drawings is merely used for the purpose of illustrating 90 the application of the invention, as obviously the invention may be used in connection with any construction of wind mill adapted to impart a reciprocating motion to the pump rod.

95 What is claimed is:—

1. A balance device comprising a rectangular web, means for securing said web at its corners to a support, tension springs secured to said means adjacent the corners of 100 the web, and means connecting the springs to a reciprocating element.

2. A balance device comprising a rectangular web, extensions formed on the corners of said web and angularly related and 105 secured to a support, tension springs secured to said extensions adjacent the corners of the web, and an attaching member secured to the springs and to a reciprocating element.

3. A balance device comprising a web,
means for securing the web to a support,
relatively spaced tension springs secured to
said means, a pair of clamping plates having
5 angularly related ends secured to the springs,
and means securing the plates together and
to a reciprocating element.

In testimony whereof I affix my signature
in presence of two witnesses.

WILLIAM HENRY WINSLETT.

Witnesses:

G. B. PALM,
EUGENE WILSON.
